F. P. KLUND

MACHINE FOR THICKENING PULP

Filed July 3, 1925

Inventor.
Frederic P. Klund
By A. M. Stangor
Atty.

UNITED STATES PATENT OFFICE.

FREDERIC P. KLUND, OF ERIE, PENNSYLVANIA.

MACHINE FOR THICKENING PULP.

Application filed July 3, 1925. Serial No. 41,357.

- This invention relates to improvements in apparatus for expressing liquids, carried in suspension, from fibrous or granular material.
- 6 The object of my invention is to provide mechanism to receive pulp which has been gathered by means of any of the well known revolving screen types of apparatus from a "soup tank" in the form of saturated pulp, 10 and express therefrom excess free water, and deliver it for any of the uses for which the pulp is adapted.
- The object of the present invention is, therefore, to provide suitable mechanical 15 means whereby a continuous supply of liquid impregnated fibrous or granular material will be placed upon a travelling screen and a squeezing pressure applied thereto which will be maintained for a substantial period 20 of time while the liquid therein escapes therefrom through the screen.
- The features of my invention consist of a travelling screen, composed of perforated metal, or wire mesh, or both, means to spread 25 upon the exterior of the upper portion thereof a layer of liquid impregnated material, and a travelling pressure platen which will press the layer of material against the screen and maintain the pressure, giving the liquid 30 time to flow out of the material and drop from the screen.
- These and other features of my invention will appear hereinafter and are illustrated in the accompanying drawings, in which:—
- 35 Figure 1 is a side elevation, partially in section, of my improved pulp drying mechanism.
- Figure 2 is a like view of a modification of the same.
- 40 In these drawings A indicates a screen cylinder, having a shell composed of screen material suitably reinforced, in the usual manner, to resist the pressure of the press apparatus.
- 45 B indicates a hopper which is co-extensive with the length of the cylinder, and is provided with an adjustable gate C, which is provided with an operating hand screw D by means of which the gate C can be raised 50 or lowered to increase or diminish the width of the discharge opening of the hopper B through which the material to be operated upon flows upon the periphery of the screen cylinder. The cylinder A may be provided 55 with a radial flange A' at each end thereof which is adapted to form the edges of the layer of material as it is laid upon the cylinder A.
- E and F are rollers mounted parallel with and adjacent to the cylinder A, upon which is placed a flexible belt G which continuously presses the layer of material firmly against the periphery of the cylinder A. The roller F is preferably closer to the cylinder A than the roller E so that the pressure of the belt 60 G against the layer of material gradually increases between the rollers E and F.
- The rollers E and F are preferably provided with adjusting mechanism (not shown) of usual and ordinary construction, 65 whereby the same may be adjusted with relation to the cylinder A, and may be provided with driving gear (not shown) adapted to ensure identical rotative speed with the cylinder A.
- I also provide a trough H to catch the liquid expressed from the material operated upon, and convey it from the apparatus.
- J indicates a conveyor mechanism to supply the liquid soaked material to the hopper 70 B, and K indicates material being conveyed thereby to the hopper B.
- The trough H is provided with a doctor or scraper H' which is pivoted thereon, and is provided with a lever h in which is placed a hand screw h' adapted to operate said lever h to swing the upper edge of said scraper toward or from the cylinder A so that the same can be adjusted to properly scrape the material off of the cylinder.
- I also provide a suction box M from which air can be exhausted for the purpose of clearing the perforations in the shell of the cylinder of particles of material which tend 80 to clog the same.
- L and L' indicate press rolls between which the material may be passed to compact the same, or to form the material into sheets of a uniform thickness. M' indicates a spray tube installed within the cylinder A, 85 and adapted to direct sprays of water against the inner surface of the screen, for the purpose of cleaning the screen of any particles of fibres which may adhere to the exterior surface thereof which may not be washed therefrom by the water falling from the upper portion of the screen.
- In Fig. 2 I show a modification B' of the hopper, in which the gate C is eliminated, and the roller E and flexible belt G thereon 95

project into the hopper, so that the travelling belt, and screen A, act upon the material to draw the same therebetween.

In operation, the screen A is not submerged. The material from which liquid is to be removed after having been gathered from a "soup" tank by any of the well known cylinder screen machines is deposited on the carrier J by which it is delivered 5 into the hopper B and thence to the upper portion of the screen, in an even layer of predetermined thickness. The thickness is determined by the gate C, when a gate is provided. When the material is placed on 10 the screen A, a certain amount of free liquid flows therefrom at once by reason of gravity, and then as the layer of material passes under the roller F, pressure is applied, which is not released when the material 15 passes from under the roller E, but is maintained, or may be increased, by the flexible belt G for an appreciable period of time, according to the speed of revolution, until the material passes from between the 20 roller F and the screen, thereby giving time for a greater amount of liquid to be released from the material and drop from the screen, so that it will not be re-absorbed when the pressure is released when the material passes 25 from between the roller F and the screen, thus permitting the output to be greatly increased with a high degree of dryness and of a thickness that it will not adhere to the under side of a felt.

30 The advantages of this invention are that it is simple in construction, that it is capable of a high output, and that the product is much greater in quantity and contains much less moisture than the product of any of the 35 machines as at present constructed.

40 After leaving the screen A the layer of material is passed between press-rolls L and L', or a succession of such rolls, until it is 45 compacted sufficiently for the purpose desired.

Having thus fully described my invention so that others can utilize the same, it is obvious that many changes can be made therein without departing from the scope of my invention, therefore what I claim as new and 50 desire to secure by Letters Patent is:—

1. In an apparatus of the class described, a moving screen to receive a layer of material, a moving press device to press said material against said screen, and suction box mechanism to draw loose fibers of said material out of the openings in said screen. 55

2. In an apparatus of the class described, a moving screen, means to place a supply of material on said screen, a moving press device acting in opposition to said screen, and means to clear said screen of loose fibers of material. 60

3. In an apparatus of the class described, a moving screen, conveyor mechanism to 65 carry material to said screen, a moving pressure device acting in opposition to said screen.

4. In an apparatus of the class described, a moving screen, a hopper adapted to receive 70 material and direct it upon said screen, conveyor mechanism to carry material to said hopper, and a moving press device acting in opposition to said screen to express excess fluid from said material. 75

5. In an apparatus of the class described, a moving screen mechanism, a moving pressure device adapted to exert pressure in opposition to said screen, a hopper adapted to direct material between said screen and pressure device, and a conveyor mechanism to supply material to said hopper. 80

6. In an apparatus of the class described, a moving screen, a hopper adapted to receive and support a vertical column of material 85 upon said screen, and a travelling pressure device adapted to engage said material and press it against said screen.

In testimony whereof I affix my signature.
FREDERIC P. KLUND.
